UNITED STATES PATENT OFFICE.

HENRY CARTER AND LOUISE AUGUSTIN, OF PONTIAC, MICHIGAN.

SLOP-PAIL OR COMMODE.

SPECIFICATION forming part of Letters Patent No. 392,182, dated November 6, 1888.

Application filed July 5, 1888. Serial No. 279,152. (No model.)

To all whom it may concern:

Be it known that we, HENRY CARTER and LOUISE AUGUSTIN, citizens of the United States, residing at Pontiac, in the county of 5 Oakland and State of Michigan, have invented certain new and useful Improvements in Slop-Pails or Commodes, of which the following is a specification, reference being had therein to the accompanying drawings.

10 This invention relates to new and useful improvements in slop-pails or commodes for use in sick-rooms for invalids, or for prison use where portable commodes have to be provided.

15 Our invention consists in the peculiar construction, arrangement, and combination of the parts, whereby all sanitary requirements are complied with, while at the same time the article is very simple in its construction 20 and can be manufactured by ordinary skilled workmen, all as more fully hereinafter described.

In the drawings which accompany the specification, Figure 1 is a perspective view of the 25 improved device. Fig. 2 is a plan thereof. Fig. 3 is a vertical central section on line *x x* in Fig. 2.

A is a pail of ordinary construction—such as found in the market for water or slop 30 pails—and this is provided with the usual bail or handle, B. A pail of this kind we provide upon two opposite sides, near the top, with the spring-catches C, the hooked ends D of which are brought to a level with 35 the top edge of the pail, suitable notches being provided to this end in the top edge of the pail to allow the free movement of the spring.

40 There are suitable handles on these spring-catches for the purpose of operating them.

F is the seat of the commode, and this is made to fit within the top of the pail to make it level therewith, a suitable shoulder, G, being formed near the top of the pail to rest 45 the seat thereon, and recesses H are formed on top of the seat for the purpose of allowing the hooked ends D of the spring-catches to engage therein and secure the seat removably upon the top of the pail.

I is the cover, of corresponding or slightly- 50 larger diameter with the top of the pail, which is made in two parts, the part J being stationary and secured in a suitable manner to the seat F, while the part I is hinged to the stationary part.

55 By good workmanship in constructing this device a tight-fitting cover can be easily obtained, which will prevent any disagreeable odors from finding their way out if the cover is kept closed; and, to prevent the wood from 60 being stained or tainted, the inside should be liberally varnished or covered with some water-proof paint or tar.

If desired, a vessel of porcelain, metal, or other material may be placed inside of the 65 pail.

70 It will be seen that, the parts being so readily, detached merely by drawing on the handles E of the catches, the device can be kept scrupulously clean without any difficulty, and if the device becomes foul it can be renewed, in part or in whole, without any expense, as the pail is of such description as can be found in the market anywhere. To make the device less conspicuous in the room, 75 a little upholstering on the top cover and other disguising means practiced by the ordinary housewife will readily transform the article into a piece of furniture deprived of every unsightly feature, if occasion should require.

80 For prison or other use the device, if not used for a commode, is not in any way rendered unserviceable, as by taking the seat and cover off the ordinary pail is intact and fit for 85 use, as before.

What we claim as our invention is—

1. The combination of the pail, the spring-catches secured thereto upon opposite sides near the top, and the seat removably retained 90 within the top by the spring-catches and seated therein on an annular shoulder, and the cover secured to the seat and having the hinged and stationary portion, substantially as described.

95 2. In a commode, the combination of the pail A, the spring-catches C, secured thereto and provided with the handles E, and the

hook D, engaging into a recess on top of the pail, the seat F, removably supported on a shoulder inside of the pail and level with the top thereof, the recesses H on top of the seat, and the cover, consisting of the part J, secured to the seat, and the hinged portion I, substantially as described.

5 In testimony whereof we affix our signatures,

in presence of two witnesses, this 29th day of June, 1888.

HENRY CARTER.
LOUISE AUGUSTIN.

Witnesses:

WM. BRENNER,
LOUISE BEENNER.
